COP WINDER

Henry C. Beecher, 1521 Clarkson St., Baltimore 30, Md.
 Filed Jan. 20, 1958, Ser. No. 710,065
 9 Claims. (Cl. 242—27)

This invention relates generally to machines for manufacturing devices employed in the art of weaving, and the like, and more particularly it pertains to an improved machine for the winding of cops, which are specially wound bodies of yarn for use on weaving machines.

In the manufacture of cops on existing machines, an individual spool, or bobbin, is required for each cop. These spools are of wood or other rigid material, and, because of their cost, and or expenses incurred in storing and handling them, the spools add measurably to the cost of the finished cop. Other limitations of existing cop winding machines are their large size, complexity, and need for frequent operator attention and adjustment.

It is, therefore, a principal object of this invention to provide a new and improved cop winding machine which fashions self supporting cops, of perfect form and tension, entirely without the use of individual spools or bobbins.

Another object of this invention is to provide a copping machine that winds cops sequentially and rapidly, cutting off and ejecting each cop as it is made, in a continuous, automatic process.

A further object of this invention is to provide a copping machine in which the length of the cops produced is variable through a considerable range of adjustment.

A further object of this invention is to provide a copping machine, which is compact in structure, and economical and reliable in operation.

Another object of this invention is to provide a new and improved copping machine in which yarn from a suitable supply is fed, under controlled tension, through a traversing mechanism and onto interim spool means, including a rotating spindle, on which the yarn is wound into cop form, and from which the finished cop is severed and ejected, all by automatically operating mechanisms.

These and other objects of this invention will become more readily apparent through examination of the drawings, which describe a single embodiment of the device, and in which:

FIGURE 1 is a perspective view of the machine with cover in place;

FIGURE 2 is a rear elevation of the machine;

FIGURE 3 is an elevation in partial section taken on line 3—3 of FIGURE 2;

FIGURE 4 is an elevation, in partial section, taken on line 4—4 of FIGURE 3;

FIGURE 4-A is a sectional diagram in plan view of the clutch and shifter assembly of FIGURE 4;

FIGURE 5 is an enlargement of a detail of FIGURE 1;

FIGURE 6 is a detail, in side view, of the cop length gauge assembly of the machine;

FIGURE 7 is a detail, in plan view, of the main winding shaft, and of the forward terminal portion of the cop length gauge assembly of FIGURE 6;

FIGURE 8 is a detail, in left side elevation of the traversing mechanism of the machine;

FIGURE 9 is a detail in perspective, and in partial section, showing the nut and associated parts, of the cop length gauge assembly of FIGURE 6;

FIGURE 10 is a detail in perspective of the step and follower of FIGURE 4-A;

FIGURE 11 is an axial view of the traveller plate; which guides parts of the machine in operation;

FIGURE 12 is a perspective view of a grooved shelf, which buides parts of the machine in operation;

2

FIGURE 13 is a detail in perspective of the yarn snipping knives;

FIGURE 14 is a plan view of a finished cop;

FIGURE 15 is a diagram of the machine's power supply; and

FIGURE 16 is a detail, in partial section, along line 16—16 of FIGURE 4.

Referring now to FIGURE 1, and to FIGURE 5, which is a detail of FIGURE 1 enlarged, the motions and structures of those parts of the copping machine which actually touch the yarn will be described, after a brief account is given of the gross exterior features of the machine. Description of the remainder of the machine, including the internal structures which drive and synchronize its various parts, will be given subsequently.

The machine 45, as shown in FIGURE 1, rests on a platform 13, supported by angle iron frame 10. A lower platform 11 holds the drive motor 12. A removable casing 75 covers much of the machine.

The cop 80, as shown in FIGURE 14, which consists of a quantity of yarn wound in a particular manner, is formed directly on spindle 84, as shown in FIGURE 5, which rotates continuously.

As a strand of yarn 40, as shown in FIGURE 1, from a suitable source of yarn, is fed downwardly onto the spindle through slot 87 in funnel 72 with the strand being oscillated continually from one end of the spindle to the other by a traversing fairlead 32, which is fixed on axially oscillating shaft 30. This combination of winding and oscillation produces a body of smoothly overlapped layers of yarn on the spindle. As this wound body, or cop, increases to the maximum diameter, which can be held inside funnel 72, it is gradually and continuously forced off the tapered spindle by the incline of the funnel bore, and so increases in length gradually and continuously.

Initial increase in cop length brings the advancing end 113, as shown in FIGURE 14, of the cop into contact with a rotatable headpiece 39, as shown in FIGURE 1, which is mounted on a slidable channel member 33 extending through the structure 45. Continued increase in cop length proportionally forces the headpiece 39 axially away from the spindle 84.

When it has been displaced a predetermined distance (the cop-length setting) by increase in cop length, the headpiece, acting on channel 13, actuates mechanisms which remove it from contact with the cop, sever the strand of yarn 40 from the cop, and eject the cop from the machine by causing funnel 72 to move the cop axially of the spindle 84. The cop falls from the machine into any suitably placed container means, and the machine resets itself and winds further cops as required, in the automatic sequence described.

It should be noted here that the cop is cut free at a point between cop and spindle, not between spindle and yarn supply, so that the spindle is at all times engaged to the supply of yarn. The cutting function will be explained further subsequently.

Thus, in the manner described, coreless, self supporting cops are produced by the machine of this invention, in contrast to cops which must be wound on expensive individual spools, if produced by conventional cop winders.

FIGURE 1 also shows the structures for holding the spool of supply yarn, and for dispensing the yarn uniformly. Mast 74, fixed vertically to the top of casing 75, supports the spool of yarn 73, from which the strand 40 is pulled by spindle 84. The strand is pulled from the spool 73 through fairleads including disk 78 and eyelets 81, and through a spring-loaded friction sheave 77, of conventional split form, which keeps the yarn suitably taut for cop winding. Continuing, the yarn passes over arm 82 of switch 83.

In case of yarn breakage, the arm 82 is no longer de-

pressed by yarn tension, and under pressure of spring means, not shown, rises and opens switch 83. As shown in FIGURE 15, this interrupts the flow of electric current through conductor 79, and stops the drivemotor 12, and the cop winding machine.

Continuing past the switch arm, the yarn passes finally through the traversing mechanism and the opening in the funnel, and is made up in cop form on the spindle and against the headpiece, as previously described.

FIGURE 3 best shows the methods of actuation of the machine, and largely shows the machine proper. Housing the machine, and bearing many of its parts are rear wall 14, left side wall 17, and front wall 15. Right side wall 16 is not shown in this sectional view.

The housing comprised of the walls is open at the top, but includes a floor 89 at the bottom. This floor is preferably bolted to platform 13 shown in FIGURE 1, suitably matched holes being provided in both structures for the purpose.

Openings (not indicated on the drawings) provide for passage of belt 22 which transmits power from the drive motor to the machine, and for cable 94. Sheave 93 is also mounted on floor 89 to carry the cable 94 that suspends counterweight 90.

A winding shaft 18, which is detailed separately in FIGURE 7, runs longitudinally through the structure 45, FIGURE 3, and is journaled in bearings 20. It bears integrally fixed in its end the spindle 84, FIGURE 5, on which the yarn is wound into cops. The spindle is of polygonal cross-section to give it greater purchase on the yarn. A pulley 21 on the winding shaft is aligned with the pulley 23 on the drive motor 12, FIGURE 2, with the transmission belt 22 connecting them. The shaft 18 is employed to transmit power to two auxiliary shafts 19 and 29 and their respective mechanism. The auxiliary shaft 19 actuates axially oscillating shaft 30, FIGURE 3, through the eccentric 26, the pin 27, and the connecting rod 28. These parts are shown separately, in subassembly, in FIGURE 8. The traversing fairlead 32, adjustably clamped to shaft 30, guides the yarn 40 in spreading it over the cop being wound, as was explained in connection with FIGURE 1. The shaft is suitably journaled in the walls of the structure 45. The fairlead 32 is made adjustable on shaft 30 lengthwise, to enable it to be accurately positioned to suit its work. The shaft 19 gets its power from the worm 24 meshing with the gear 25, keyed to it. The traversing mechanism runs continuously with the shaft 18. In contrast with shaft 19, and its traversing mechanism, which run continuously, shaft 29, with its train of mechanism, is driven intermittently by shaft 18 through a clutch. The purpose of this intermittent drive of shaft 29 is to actuate the funnel and knives which eject and cut free each cop after it is completed, in a manner now to be explained in detail.

As shown in FIGURE 4, shaft 29 is journaled in plate 17. The shaft has a clutch 95, FIGURE 4 and 4-A, slidably keyed to it, and tensioned by a spring loaded plunger 96 in a lateral direction. A traveler plate 50 of circular form is fixedly mounted on the shaft 29 and is rotated with it when the prongs 97, FIGURE 4-A, of the clutch 95, are forced, by the tension of the spring 96 into recesses 98 in the hub 92 of the gear 63. Gear 63 is driven continuously by worm 85 on shaft 18, and turns freely on shaft 29 when clutch 95 is disengaged. As shown in enlarged detail in FIGURE 10, as well as in FIGURE 11, a step 100 projects from the left lateral face of the traveler plate 50, and is contoured angularly to facilitate the movement of a conventionally designed shifter 101 to de-clutch the clutch 95. The shifter 101 is hinged on pin 116 and is surmounted with a freely socketed ball, 102 to reduce the friction on contact with the step 100. The shifter 101 is connected to the traveler plate 50 by a connecting element 101', as shown in FIGS. 4 and 10. A circular ledge 103 thick enough to provide long wear in service as a path on which the ball bears is shown in FIGURE 10. This ledge is not essential, and is not shown

elsewhere in the drawings. When the ball 102 of shifter 101, FIGURE 4-A, is brought into contact with the step 100 by rotation of traveler plate 50, the shifter is pivoted laterally until it disconnects the clutch 95 from the gear 5 hub 92, and the clutch and traveler plate stop. The step 100 is of relatively short angular length, subtending about 10° of arc on the traveler plate. Its purpose is simply to stop the traveler plate at the proper moment, and then when the plate is slightly rotated by pawl means, to slip the clutch into contact, so that the plate can further travel through some 350°. The short push required to move the traveler plate the remaining 10° (approximately) is furnished by the pawl mechanism 48, FIGURE 16, pushing against notch 49 in the peripheral face of the traveller plate, as will be explained later in connection with FIGURE 16.

As shown in FIGURES 3 and 4, a connecting rod 60 at one end is pivoted eccentrically on the side of traveler plate 50, and at its other end is pivoted to doffing beam 61, in such manner that rotation of the traveler plate gives a reciprocating stroke to the doffing beam. The doffing beam 61 is supported on rollers 62, FIGURES 4 and 16, which are suitably attached to wall 16. The rollers reduce friction, during operation of the beam. The doffing beam 61 as shown in FIGURE 3, runs longitudinally in the structure 45 and passes through the front wall 15 into a carriage 64 to which it is integrally fastened and which it reciprocates. As best shown in FIGURE 5, the carriage 64 is of angular form, its back wall 66 in the retracted position coming back against the front wall 15, its bottom 67 encompassing and being guided by the outer edges 104 of shelf 65. Spindle 84 passes through a hole in the back wall of carriage 64. The shelf 65 is rigidly attached to front wall 15 and has grooves 68, FIGURES 5 and 12, in its top surface throughout its length. The grooves 68 are converged as shown, and serve to give a transverse travel to the tongues 69 projected from the bottom of knives 70, FIGURE 13. The knives 70 are flat and of suitable thickness to slide laterally in a vertical internal slot in the back wall 66 of the carriage 64 and against each other. The tongues 69, FIGURE 13, extend vertically down from the bottom of the knives into the horizontally disposed grooves 68, FIGURE 12, so that when the carriage 64, FIGURE 5, moves near its extreme forward position, at which point the knives are clear of spindle 84, the knives will slide sidewise or transversely with respect to the axis of the spindle and cause the knife edges 88 to pass one another in a shearing manner to sever the yarn and free the completed cop. The enlarged circular slots 86, FIGURE 13, in the knives allow them to clear the spindle when the carriage 64 is in the retracted position, as in FIGURE 5.

The doffing beam 61 with its carriage 64 is at the end of its forward stroke when cop severance and ejection completed. Then as the traveler plate continues to rotate, it brings the carriage 64 back, the knives 70 opening as it does so allowing the yarn to wind continuously on the spindle 84. The end of spindle 84 is tapered and of polygonal cross-section to facilitate the winding of the yarn on it and to allow slipping of the finished cop. At 60 the end of the stroke on the return, the step 100 on the traveler plate moves the shifter and clutch and stops the traveler plate. As previously stated, spindle 84 extends through an opening in the carriage when the carriage is positioned against the wall 15, as in FIGURE 5, and into a funnel 72 attached to the wall 66. As said, the funnel is open at the top as indicated at 87 to permit the yarn 40 to oscillate easily and at the same time form a mold for the cop end portion. The opposite end portion of the cop is formed by frustum head piece 39. The opposition of spindle and headpiece is best seen in FIGURES 1 and 7.

Cop length is controlled, as was explained in connection with FIGURE 1, by headpiece 39, through its attached gauging mechanism. FIGURE 6 details the structure of this gauging subassembly, which in essence simply

bears the headpiece and an adjustable stud 37. The structure comprises headpiece 39, axle 41 on which it rotates, bracket 42 which affixes axle 41 to channel 33 rigidly and in parallel alignment, counterweight clamp 119, whose function will be explained later, longitudinal slot 38 in channel 33, screw 34 which is conventionally journalled in channel 33 so that it can rotate freely but not translate, knurled wheel 36 affixed to screw 34, nut 35 on the screw, stud 37 affixed to the nut in such manner as to act both as a nut wing and as an actuating stud, and pointer 108 affixed to the stud 37. FIGURE 9, a partial section, details the nut and its immediately associated parts in perspective. Graduations of the cop-length scale 110 to which pointer 108 refers, can be seen on the channel. As shown in FIGURE 1, channel 33 extends beyond the carriage 64 in front of the housing structure 45 at one end, and beyond the rear wall 14 at the other. Where the channel extends rearwardly, wheel 36 enables the user to turn the screw 34 and adjust the nut 35 to suit the length of cop required, referring to graduations on the cop-length scale 110 to which the pointer 108 on the stud 37 is directed. The walls 14 and 15 have square holes in them for the member 33 to pass through and to hold it in line and prevent rotation.

A detailed operation of cop-length control in the copping machine of this invention will now be given. As indicated, the cop 80 in being wound, is made up on the spindle 84 within the funnel 72 and against the headpiece 39, FIGURE 1. As the cop is built up on winding, it increases in length. As the length increases, the cop pushes against the headpiece 39 and forces it outwardly. The bracket 42 and channel member 33 follow in the direction in which the headpiece is pushed by the enlarging cop, until, eventually as shown in FIGURE 16, a left side elevation, the stud 37 on nut 35, set at the desired cop length, comes into contact with the tooth 43. As further shown in FIGURE 16, the tooth 43 is extended from a latch 44 that is movably connected by a hinge 59 to one end of a lever 47, which is pivoted on a stationary pin 46 near its center. The pin 46 is attached to the wall of the housing structure through bracket means, not shown. A pawl 48 extends from the lever 47 and engages a notch 49 in the traveler plate 50 when the latch 44 is moved towards the front or left, through action of stud 37 on tooth 43. This rotates the traveler plate clockwise about 10°. The pawl 48 is held against the traveller plate by spring means, not shown.

The latch 44 has its free front end 56 angularly formed and disposed beneath and against the upper jaw 57 of a horizontal hasp 58 which is rigidly supported by the housing 16. A spring jaw 111 of the hasp resiliently supports the latch-end upwardly. When the latch 44 is moved towards the front (that is to the left), the hasp 58 tilts it downwardly, until at the end of the stroke, the stud 37 is released from the tooth 43. Stud 37 is next engaged by cam 120 affixed to the side of the traveler plate, and through the stud, during subsequent rotation of the traveler plate, the cam pushes headpiece 39 well free of the cop. The latch 44 then springs back to become inoperative. The aforesaid 10° rotation of the traveler plate by the pawl 48 is enough to move the step 100 from under the shifter 101 and bring the clutch 95, FIGURE 4, into action. The traveler plate continues to rotate under power from gear 63 to which it is now engaged. When the gear drive takes over, the carriage 64 is moved forward by connecting rod 60, FIGURE 3, the snipping of the yarn by the knives 70 follows, and the cop is ejected. The carriage retreats with the yarn continuing to wind on the spindle. The headpiece, bracket, and channel follow, being pulled back by the counterweight 90. The counterweight is fastened to adjustable clamp 119 on channel member 61 by a cable 94 passing over sheave 93, the latter being supported by the floor 89. The cable passes downwardly, over the sheave, to the counterweight 90. The traveler plate 50, FIGURE 16, stops automatically when the step 100 throws the clutch 95 and dis-

connects it from the driving gear 63. At this instant its notch 54 is caught by pawl 53 and the traveler plate is stopped from overrunning. Pawl 53 is automatically disengaged, at the start of the next cycle of operation of the traveler plate, by pivotal action about pin 46 when latch 44 is moved forward.

In the foregoing account of how cops are wound, and their lengths set, on the improved copping machine of this invention, no measure has been given of the longest 10 cop which can be made on the machine. The size of the cop so produced is limited by its capacity to sustain itself. Practically, this is not a problem, as the conventional length of a cop is less than 12 inches. In special 15 cases where considerably greater length may be required, it is simply necessary to provide greater depth to achieve the necessary rigidity.

While but one construction of the invention has been illustrated in the drawings and described herein, it is not intended to limit its design and manufacture to such particular form, as it is appreciated that other structures 20 could be designed and made that would use the same principles and come within the scope of the appended claims.

What is claimed is:

- 25 1. A cop making machine, comprising, a housing structure having spaced walls, a spindle journalled in said housing structure, traversing means, means for rotating said spindle and for driving said spindle and traversing means in synchronism, said traversing means including an oscillating shaft bearing a fairlead for supplying yarn from end to end of said spindle during cop winding, a measuring bar arranged parallel with respect to said spindle and axially positionable in said housing structure to control cop length and including a piece longitudinally adjustable on said bar, a headpiece on said bar disposed in alignment with an end of said spindle, a clutch discon-nectably linked in rotation with said spindle and engaged thereto by action of said longitudinally adjustable piece when said headpiece is pressed away from the end of said 30 spindle by the cop being wound, a traveler plate affixed in rotation to said clutch, cam means on said plate to disconnect said spindle and plate through said clutch on selected rotation of said plate, means for controlling the amount of rotation of said plate, a doffing beam jour-nalled in said housing, means on the traveller plate for propelling said doffing beam through its travel as the said plate revolves, a carriage including a projection thereon to encompass said spindle, said carriage being operated by said doffing beam to force said cop off said spindle, a knife on the carriage to cut the yarn and free the com-pleted cop, an extension on the front of said housing structure to guide said carriage and said knife, and means for returning said measuring bar towards said spindle after said cop is ejected and simultaneously as said traveller plate rotates to its first position, disconnects said 35 clutch and stops, awaiting formation of a subsequent cop to reoperate the aforementioned parts.

2. A cop-making machine, comprising, a housing structure having a plurality of walls predeterminedly spaced around one another, a main winding shaft jour-nalled longitudinally in said housing structure and adapted to rotate in a predetermined direction, means for rotating said shaft, plural gearing on said shaft ro-tatable therewith, an auxiliary second shaft connected with said gearing and angularly disposed with respect to said main shaft, an eccentric mounted on said second shaft and rotatable therewith, a connecting rod actuated by said eccentric, a traversing member mounted on said rod including bifurcated jaws for manipulating a length of yarn passed transversely therebetween and to-wards said main shaft to be wound thereon as it rotates to form a cop, means for supplying the said yarn under tension, a measuring bar longitudinally positioned in said housing and arranged parallel with respect to said main shaft, said bar being adjustable in the housing to control 40 45 50 55 60 65 70 75

the size of said cop and including a stud projecting laterally therefrom, a headpiece on said bar disposed in alignment with an end of said main shaft on which said cop is to be wound and adapted to exert pressure in the direction thereof to carry compact said cop as it is being wound, a cam shaft transversely positioned in said housing and rotated by a second portion of said gearing, a clutch rotated by said main shaft and shifted by said stud when said headpiece is retracted by being pressed away from the end of said main shaft as said cop is wound to its full size, said clutch rotatably connecting said main shaft to said cam shaft to rotate it, a traveler plate keyed to said cam shaft and rotatable thereby, a lug on the said plate for facilitating the operation of said clutch through a follower on the rotation of said plate, means on said traveler plate for controlling the amount of rotation of said plate induced through the actuation of said clutch; a doffing beam movable in said housing through a predetermined travel, means on said traveler plate for propelling said doffing beam through its travel as said plate revolves, a carriage including a projecting cup on the front thereof encompassing the end portion of said main shaft and serving as a guide for shaping said cop during winding, said carriage being operated by said beam to force said cop off said main shaft, knives in said carriage for cutting said yarn on the completed cop, a shelf mounted in front of said housing for said carriage to ride on, groove means in the shelf for guiding said knives through their cutting movements as said carriage rides thereon, means connected with said measuring bar mounted on said housing for returning it and said carriage to their normal positions after said knives have cut said yarn in predetermined sequence and simultaneously as said traveler plate and propelling means for said doffing beam rotate to their first positions and disconnect said clutch and stop awaiting the formation of a subsequent cop to reoperate the aforementioned parts.

3. A cop machine, comprising, a housing having a plurality of walls predeterminedly spaced about each other, a winding shaft journalled therein and extending longitudinally with a portion extending beyond the front wall thereof, a motor for rotating said shaft connected by a transmission thereto, an eccentric mechanism including an oscillatable traversing member operated by said shaft, said traversing member being adapted to guide a yarn passing therethrough, a mast situated above said housing for rotatably holding a spool of yarn thereon for unwinding, a holder secured to said housing, tension discs and guides mounted on said holder for guiding said yarn under tension from said spool, through said traversing member, to said winding shaft, a carriage adjacent to and reciprocable in front of said housing, a shelf for supporting and guiding said carriage, said carriage including an opening from its top, a funnel member with a slot longitudinally provided therein in alignment with said opening, projectably attached to the front of said carriage, knife means movable in said carriage across said opening, the yarn to said winding shaft from said traversing member passing through said slot and opening and between said knife means while winding, means on the shelf for actuating said knife means when the carriage is reciprocated to cut the yarn in a predetermined position thereon, a calibrated rod adjustable in said housing for measuring said cop having means thereon for controlling its position therein, a clutch mechanism, means for shifting said clutch mechanism, a traveler plate mounted on said housing actuated by said winding shaft when started by said clutch mechanism, means on said plate connecting said rod with said plate when moved to a predetermined position by said cop as it winds to completion, a doffing beam slidable in said housing, means on the said plate for reciprocating said beam, and means connecting said beam and said carriage for actuating them together and causing said completed cop to be ejected.

4. A cop machine, comprising, a housing having a

plurality of walls predeterminedly spaced about each other, a winding shaft journalled therein and extending longitudinally with a portion extending beyond the front wall thereof, a motor for rotating said shaft connected by a transmission thereto, an eccentric mechanism including an oscillatable traversing member operated by said shaft, said traversing member being adapted to guide a yarn passing therethrough, a mast situated above said housing for rotatably holding a spool of yarn thereon for unwinding, a holder secured to said housing, tension discs and guides mounted on said holder for guiding said yarn under tension from said spool, through said traversing member, to said winding shaft, a carriage adjacent to and reciprocable in front of said housing, a shelf for supporting and guiding said carriage, said carriage including an opening from its top, a funnel member having a slot longitudinally provided therein in alignment with said opening, projectably attached to the front of said carriage, knife means movable in said carriage across said opening, the yarn to said winding shaft from said traversing member passing through said slot and opening and between said knife means when said carriage is reciprocated to cut said yarn in a predetermined position thereon, a calibrated rod adjustable in said housing for measuring said cop having means thereon for controlling its position therein, a clutch mechanism, means for shifting said clutch mechanism, a traveler plate mounted in said housing actuated by said winding shaft when started by said clutch mechanism, means on said plate connecting said rod with said plate when moved to a predetermined position by said cop as it winds to completion, a doffing beam slidable in said housing, means on the said plate for reciprocating said beam, means connecting said beam and the carriage for actuating them together, and a removable cover for said housing including means for retaining said mast and spool thereon.

5. A cop machine, comprising, a housing having a plurality of walls predeterminedly spaced about each other, a winding shaft journalled therein and extending longitudinally with a portion extending beyond the front wall thereof, a motor for rotating said shaft connected by a transmission thereto, an eccentric mechanism including an oscillatable traversing member operated by said shaft, said traversing member being adapted to guide a yarn passing therethrough, a mast situated above said housing for rotatably holding an unwinding spool of yarn thereon, a holder secured to said housing, tension discs and guides mounted on said holder for guiding said yarn under tension from said spool, through said traversing member, to said winding shaft, a carriage adjacent to and reciprocable in front of said housing, a shelf for supporting and guiding said carriage, said carriage including an opening from its top, a funnel member having a slot longitudinally provided therein in alignment with said opening, projectably attached to the front of said carriage, knife means movable in said carriage across said opening, the yarn to said winding shaft from said traversing member passing through said slot and opening and between said knife means while winding, a calibrated rod adjustable in said housing for measuring said cop having means thereon for controlling its position therein, a clutch mechanism, means for shifting said clutch mechanism, a traveler plate mounted in said housing actuated by said winding shaft when started by said clutch mechanism, means on said plate connecting said rod with said plate when moved to a predetermined position by said cop as it winds to completion, a doffing beam slidable in said housing, means on the said plate for reciprocating said beam, means connecting said beam and said carriage for actuating them together, a removable cover for the housing including means for retaining said mast and spool thereon, said knife means including cutting edges, and means on said shelf for actuating said knife means including grooves forming rails in which portions of said knife means are engaged and guided to a position for

cutting said yarn and to a withdrawal position as said carriage is reciprocated.

6. A cop machine, comprising, a housing having a plurality of walls predeterminedly spaced about each other, a winding shaft journalled therein and extending longitudinally with a portion extending beyond the front wall thereof, a motor for rotating said shaft connected by a transmission thereto, an eccentric mechanism including an oscillatable traversing member operated by said shaft, said traversing member being adapted to guide a yarn passing therethrough, a mast situated above said housing for rotatably holding a spool of yarn thereon for unwinding, a holder secured to said housing, tension discs and guides mounted on said holder for guiding said yarn under tension from said spool through said traversing member, to said winding shaft, a carriage adjacent to and reciprocatable in front of said housing, a shelf for supporting and guiding said carriage, said carriage including an opening from its top, a funnel member having a slot longitudinally provided therein in alignment with said opening, projectably attached to the front of said carriage, knife means movable in said carriage across said opening, the yarn to said winding shaft from said traversing member passing through said slot and opening and between said knife means while winding, a calibrated rod adjustable in said housing for measuring said cop having means thereon for controlling its position therein, a clutch mechanism, means for shifting said clutch mechanism therein, a traveler plate mounted on said housing actuated by said winding shaft when started by said clutch mechanism, means on said plate connecting said rod with said plate when moved to a predetermined position by said cop as it winds to completion, a doffing beam slidable in said housing, means on the said plate for reciprocating said beam, means connecting said beam and said carriage for actuating them together, a removable cover for said housing including means for retaining said mast and spool thereon, said knife means including cutting edges, and means on said shelf for actuating said knife means including grooves forming rails in which portions of said knife means are engaged and guided to a position for cutting the yarn and to a withdrawal position as said carriage is reciprocated, a shifter mechanism including a latch mounted on said housing and having a pawl connected therewith for ratcheting said plate.

7. A cop machine, comprising, a housing having a plurality of walls predeterminedly spaced about each other, a winding shaft journalled therein and extending longitudinally with a portion extending beyond the front wall thereof, a motor for rotating said shaft connected by a transmission thereto, an eccentric mechanism including an oscillatable traversing member operated by said shaft, said traversing member being adapted to guide a yarn passing therethrough, a mast situated above said housing for rotatably holding a spool of yarn thereon for unwinding, a holder secured to said housing, a carriage adjacent to and reciprocating in front of said housing, tension discs and guides mounted on said holder for guiding said yarn above said carriage adjacent to and reciprocatable in front of said housing, a shelf for supporting and guiding said carriage, said carriage including an opening from its top, a funnel member having a slot longitudinally provided therein in alignment with said opening, projectably attached to the front of said carriage, knife means movable in said carriage across said opening, said yarn from the traversing member to the winding shaft passing through said slot and opening and between said knife means when said carriage is reciprocated, to cut said yarn in a predetermined position thereon, a calibrated rod adjustable in said housing for measuring said cop having means thereon for controlling its position therein, a clutch mechanism, means for shifting said clutch mechanism, a traveler plate mounted on said housing actuated by said winding shaft when started by said clutch mechanism, means on said plate connecting said rod with said plate

when moved to a predetermined position by said cop as it winds to completion, a doffing beam slidable in said housing, means on the said plate for reciprocating said beam, means connecting said beam and said carriage for actuating them together, a removable cover for said housing including means for retaining said mast and spool thereon, said knife means including cutting edges, means on said shelf for actuating said knife means including grooves forming rails in which portions of said knife means are engaged and guided to cutting and withdrawal positions as said carriage is reciprocated, a shifter mechanism including a latch mounted on the housing and having a pawl connected therewith for ratcheting said plate, and a bracket on the said rod including a tapered head aligned and positioned adjacent said funnel for controlling the formation of the cop during winding and retractable therefrom while said doffing beam is moving through a predetermined portion of its travel to facilitate the ejection of said cop.

20 8. A cop machine, comprising, a housing having a plurality of walls predeterminedly spaced about each other, a winding shaft journalled therein and extending longitudinally with a portion extending beyond the front wall thereof, a motor for rotating said shaft connected by a transmission thereto, an eccentric mechanism including an oscillatable traversing member operated by said shaft, said traversing member being adapted to guide a yarn passing therethrough, a mast situated above said housing for rotatably holding a spool of yarn thereon for unwinding, a holder secured to said housing, tension discs and guides mounted on said holder for guiding the yarn under tension from said spool, through said traversing member, to said winding shaft, a carriage adjacent to and reciprocating in front of said housing, a shelf for supporting and guiding said carriage, said carriage including an opening from its top, a funnel member having a slot longitudinally provided therein in alignment with said opening, projectably attached to the front of said carriage, knife means movable in said carriage across said opening, the yarn to said winding shaft from said traversing member passing through said slot and opening and between said knife means while winding, a calibrated rod adjustable in said housing for measuring said cop having means thereon for controlling its position therein, a clutch mechanism, means for shifting said clutch mechanism, a traveler plate mounted in said housing actuated by said winding shaft when started by said clutch mechanism, means on said plate connecting said rod with said plate when moved to a predetermined position by said cop as it winds to completion, a doffing beam slidable in said housing, means on the said plate for reciprocating said beam, means connecting said beam and said carriage for actuating them together, a removable cover for said housing including means for retaining said mast and spool thereon, means on said shelf for actuating said knife means including grooves forming rails in which portions of said knife means are engaged and guided to cutting and withdrawal positions as said carriage is reciprocated, a shifter mechanism including a latch mounted on said housing and having a pawl connected therewith for ratcheting said plate, a bracket on the said rod including a tapered head aligned and positioned adjacent said funnel for controlling the formation of the cop during winding and retractable therefrom while said doffing beam is moving through a predetermined portion of its travel, to facilitate the ejection of said cop, means for guiding said doffing beam in said housing, said plate being mounted on a shaft connected by a transmission to said winding shaft to rotate in a predetermined direction when operating through the actuating of said shifter mechanism, a cam member mounted on said traveler plate and rotatable therewith with its engagement with the doffing beam designed to control the rate of its reciprocation cooperatively with the sequence to be followed in the winding and ejection of said cop and the movements of said rod.

9. A cop machine, comprising, a housing having a plurality of walls predeterminedly spaced about each other, a winding shaft journaled therein and extending longitudinally with a portion extending beyond the front wall thereof, a motor for rotating said shaft connected by a transmission thereto, an eccentric mechanism including an oscillatable traversing member operated by said shaft, said traversing member being adapted to guide a yarn passing therethrough, a mast situated above said housing for rotatably holding a spool of yarn thereon for unwinding, a holder secured to said housing, tension discs and guides mounted on said holder for guiding said yarn under tension from said spool, through said traversing member, to said winding shaft, a carriage adjacent to and reciprocal in front of said housing, a shelf for supporting and guiding said carriage, said carriage including an opening from its top, a funnel member having a slot longitudinally provided therein in alignment with said opening, projectably attached to the front of said carriage, knife means movable in said carriage across said opening, the yarn to said shaft from said traversing member passing through said slot and opening and between said knife means while winding, means on said shelf for actuating said knife means when said carriage is reciprocated, to cut said yarn in a predetermined position thereon, a calibrated rod adjustable in said housing for measuring said cop having means thereon for controlling its position therein, a clutch mechanism, means for shifting said clutch mechanism, a traveler plate mounted in said housing actuated by said winding shaft when started by said clutch mechanism, means on said plate connecting said rod with said plate when moved to a predetermined position by said cop as it winds to completion, a doffing beam slidable in said housing, means on the said plate for reciprocating said beam, means connecting said beam and

said carriage for actuating them together, a removable cover for said housing including means for retaining said mast and spool thereon, a shifter mechanism including a latch mounted on said housing and having a pawl connected therewith for ratcheting said plate, a bracket on said rod including a tapered head aligned and positioned adjacent said funnel for controlling the formation of the cop during winding and retractable therefrom while said doffing beam is moving through a predetermined portion 5 of its travel to facilitate the ejection of said cop, means for guiding said doffing beam in said housing, said plate being mounted on a shaft connected by a transmission to said winding shaft, to rotate in a predetermined direction when operating through the actuating of said shifter 10 mechanism, a cam member mounted on said traveler plate and rotatable therewith with its engagement with said doffing beam designed to control the rate of its reciprocation cooperatively with the sequence to be followed in the winding and ejection of said cop and the 15 movements of said rod, a frame for supporting said housing, and a counterpoise for facilitating the return movement of said calibrated rod away from said shifter mechanism for the winding of a new cop, said counterpoise being mounted on said frame in a position away from and 20 below said housing.
